SEPARATION OF ORGANIC COMPOUNDS

Bernard S. Friedman, Riverside, Ill., assignor to
 Universal Oil Products Company, Chicago, Ill.,
 a corporation of Delaware

No Drawing. Application September 30, 1943,
 Serial No. 504,455

16 Claims. (Cl. 196—14.35)

1

This invention relates to the separation of organic compounds having different degrees of saturation and more particularly to a novel solvent therefor and to a process using the same.

The invention is particularly applicable to the treatment of hydrocarbon fractions which, as usually recovered from various sources, contain saturated and unsaturated hydrocarbons. For example, normally liquid products of a cracking process contain olefins, aromatics, paraffins and naphthenes. Likewise, the products recovered by distillation of crude oil contain paraffins, naphthenes, aromatics and, in most cases, a small amount of olefins. Likewise, normally gaseous products of a cracking process contain olefinic gases such as propylene and butylenes, and paraffinic gases such as propane and butanes.

In many cases, it is desirable to separate the unsaturated from the saturated hydrocarbons, but this cannot be accomplished by purely fractional distillation means in practical operations because of the similarity in boiling points of the various hydrocarbons.

Other organic compounds are likewise recovered from various sources including synthetic processes wherein the products contain organic compounds of different degrees of saturation. For example, saturated and unsaturated glycerides are frequently recovered in admixture and their separation cannot be effected purely by fractional distillation in practical operations.

In a broad aspect the present invention relates to a process for separating a mixture of organic compounds of different degrees of saturation which comprises treating said mixture with a solvent comprising a substituted aliphatic nitrile. In another aspect the present invention relates to the separation of a mixture of hydrocarbons having different degrees of saturation and similar boiling points which comprises treating said mixture with a solvent comprising a substituted aliphatic nitrile, the substituent group being hydrophilic in nature.

In still another aspect the present invention relates to a process for separating a mixture of hydrocarbons having different degrees of saturation and similar boiling points which cannot readily be separated by purely fractional distillation means which comprises treating said hydrocarbons with a solvent comprising a substituted aliphatic nitrile in which the aliphatic portion contains from 2 to 5 carbon atoms inclusive, and in which the substituent group comprises at least one group selected from the class consisting of —CN, —NO₂, —NRR₁, —NRCOR₁,

2

—OR, —OCOR, —COOR, —CONRR₁, —SO₃R and —SO₂NRR₁, in which R and R₁ represent at least one of the following: —H, —CH₃, —C₂H₅, —C₃H₇, —CH₂OH, —C₂H₄OH, —C₃H₆OH, —CH₂NH₂, —C₂H₄NH₂, and C₃H₆NH₂.

The present invention is particularly applicable to the treatment of either normally gaseous or normally liquid hydrocarbon fractions for the separation of the unsaturated from the saturated hydrocarbons. As used in the present specifications and claims, the term "saturated hydrocarbons" is intended to include the paraffins and/or naphthenes, while the term "unsaturated hydrocarbons" is intended to include the olefins and/or aromatics. The olefins include both the mono and polyolefinic hydrocarbons.

Thus, the invention may be utilized for the separation of olefins and/or aromatics from paraffins and/or naphthenes. Likewise, the invention may be utilized for the separation of mono-olefins from di-olefins, the mono-olefins being less unsaturated than the di-olefins.

The present invention is characterized by a novel solvent which comprises a substituted aliphatic nitrile and may be represented broadly by the formula NCC_nH_{2n}X, wherein n is 2 to 5 inclusive and X is selected from the class as hereinafter mentioned and as will be hereinafter described in detail.

In accordance with the invention the aliphatic portion of the solvent contains from 2 to 5 carbon atoms inclusive. The term "aliphatic portion of the solvent" refers to that portion of the molecular structure as represented by C_nH_{2n} in the formula NCC_nH_{2n}X, and does not refer to the carbon atoms in the radical group or groups as represented by R and R₁. When the aliphatic portion of the solvent comprises a single CH₂ group, the nitrile group (CN) and the substituent group are both attached to the same carbon atom. Such compounds are not desired since they will decompose on heating to their boiling point, which heating is required in order to separate the solute from the solvent in a subsequent step of the process. On the other hand, when the aliphatic portion of the solvent comprises more than 5 —CH₂— groups, the effect of the polar groups is outweighed by the hydrocarbon portion of the molecules and the compound does not possess the desired selectivity.

It is a particular feature of the present invention that the substituent groups hereinbefore set forth be strongly hydrophilic; that is, they

greatly increase the solubility in water of the compound to which it is attached. Thus, while halogens increase the solubility of the compounds in water, this effect is only very slight and therefore the halogens are definitely excluded from the present invention. These compounds have high solvent power (dissolving large amounts of hydrocarbons) and high selectivity (dissolving unsaturated hydrocarbons preferentially to saturated hydrocarbons).

In accordance with the invention, the substituted aliphatic nitrile contains at least one substituent group (X) selected from the class consisting of —CN, —NO₂, —NRR₁, —NRCOR₁, —OR, —OCOR, —COOR, —CONRR₁, —SO₃R and —SO₂NRR₁, in which R and R₁ represent at least one of the following: —H, —CH₃, —C₂H₅, —C₃H₇, —CH₂OH, —C₂H₄OH, —C₃H₆OH, —CH₂NH₂, —C₂H₄NH₂, and C₃H₆NH₂.

When the substituent group comprises a nitrile (CN), the solvent will be a dinitrile as represented by succinonitrile (CNCH₂CH₂CN), glutaronitrile (CNCH₂CH₂CH₂CN), adiponitrile

and pimelonitrile (CNCH₂CH₂CH₂CH₂CH₂CN). Other suitable solvents may comprise the dinitrile compounds in which one of the hydrogen atoms is replaced by one or more of the X or R groups, provided that no more than one X group be attached to the same carbon atom. Succinonitrile is one of the preferred solvents of the present invention and is particularly suitable for use in the separation of hydrocarbons as will be illustrated in one of the examples hereinafter set forth.

When the substituent group comprises a nitro (NO₂), the solvent will be a nitro-nitrile as exemplified by 2-nitro-ethylcyanide

or similar nitro-nitrile derivatives of propane, butane or pentane. Similarly, one or more of the hydrogen atoms may be replaced by one or more of the X or R groups as heretofore set forth.

When the substituent group comprises —NRR₁, the solvent will be an amino-nitrile such as 2-amino-ethyl-cyanide (NH₂CH₂CH₂CN) or the corresponding amino-substituted propyl, butyl and amyl cyanides. Likewise, one or more of the hydrocarbon hydrogen atoms may be replaced by one or more X or R groups as hereinbefore set forth. Thus, such compounds as

or

are utilizable.

When the substituent group comprises —NRCOR, a suitable solvent may have the formula CNCH₂CH₂NHCOCH₃ or, when desired, one or more of the hydrocarbon hydrogen atoms may be replaced by an R group as hereinbefore set forth.

When the substituent group comprises —OR, the solvent may be a hydroxy-nitrile such as β -hydroxypropionitrile (HOCH₂CH₂CN) or the corresponding hydroxynitriles containing 3, 4 and 5 carbon atoms in the aliphatic portion of the molecule and in which one or more of the hydrocarbon hydrogen atoms may be replaced by one or more X or R groups as heretofore set forth. β -hydroxypropionitrile is one of the preferred

solvents of the present invention. Particularly suitable compounds include those in which the hydroxyl hydrogen is replaced by an R group, typical examples of which are cyanoethylether of ethyleneglycol (CNCH₂CH₂OCH₂CH₂OH) or the acetic acid ester of β -hydroxypropionitrile (CH₃COOCH₂CH₂CN).

When the substituent group comprises a carboxyl, (COOR in which R is hydrogen) the solvent 10 will be a cyano aliphatic acid having the formula CNC_nH_{2n}COOH in which n is 2 to 5 inclusive, and particularly CNCH₂CH₂COOH or

15 Likewise, one or more of the hydrocarbon hydrogen atoms may be replaced by one or more of the X or R groups as heretofore set forth.

When the substituent group comprises —CONRR₁, the resulting compound may be 20 called a cyano derivative of an aliphatic acid amide and may have the formula,

or if one of the hydrogen atoms attached to nitrogen is replaced by an alkyl radical such as 25 methyl, it may have the formula

When the substituent group comprises —SO₃R, the resulting compound may be a sulfonic acid 30 substituted aliphatic nitrile and may have the formula NCCH₂CH₂SO₃H. Similarly, one or more of the hydrocarbon hydrogen atoms may be replaced by one of the X or R groups as heretofore set forth.

35 When the substituent group comprises SOONRR₁, the resulting solvent will be a sulfonamide and may have the formula

40 Likewise, one or more of the hydrocarbon hydrogen atoms may be replaced by the X or R groups as heretofore set forth.

It is to be noted that there are a great number of solvents which may be satisfactorily employed 45 in accordance with the present invention, the essential limitations being that the solvent contain one or more hydrophilic groups in addition to the nitrile group, and that it will not decompose when heated to its boiling point at atmospheric pressure. It is preferred that the total number of carbon atoms in the solvent should not be too great since the solvent then is less selective, the compound exhibiting more and more the properties of an aliphatic hydrocarbon as it increases in hydrocarbon content. Thus, when the number of carbon atoms in the alkyl group is 4 or 5, the radical group preferably contains not more than 1 or 2 carbon atoms, whereas when the number of carbon atoms in the alkyl group is 2 or 3, the

50 number of carbon atoms substituted in the hydrogen atoms may be greater. In general, it may be stated that the hydrocarbon content in the solvent molecule should not exceed about 64% by weight.

65 It is understood that the various alternative compounds which may be employed in accordance with the present invention as heretofore set forth are not necessarily equivalent in their effectiveness as a selective solvent for the separation of organic compounds and particularly hydrocarbons. The choice as to the particular solvent to be employed with any given charging stock to be subjected to extraction will depend upon the characteristics of the charging stock and the type

70 75 of separation to be effected.

The solvents of the present invention are, in most cases, obtainable in the open market or, if a particular solvent is not so obtainable, it may be readily synthesized by well-known means.

The operation of the solvent extraction process is relatively simple and may comprise introducing the hydrocarbon mixture to be extracted into a suitable extraction zone. The extraction zone may or may not contain baffle plates, bubble decks, side to side pans, or the like. The extraction zone may be equipped with stirring or other contacting means in order to obtain efficient contacting of the hydrocarbons and solvent. The solvent extraction is effected under conditions of temperature and pressure in order to form an extract phase containing a major portion of the solvent and a major portion of the unsaturated hydrocarbons, and a raffinate phase containing a major portion of the saturated hydrocarbons.

The temperature employed is preferably atmospheric or slightly superatmospheric but it should be high enough to maintain the solvent in liquid phase in case it is solid at ordinary temperatures, but must be below that at which decomposition of the solvent or hydrocarbons occurs. The pressure to be employed is usually atmospheric or moderately superatmospheric but likewise should be sufficient in order to maintain the hydrocarbons and solvent in liquid phase. When treating normally gaseous hydrocarbons, a higher superatmospheric pressure is employed in order to maintain the hydrocarbons in substantially liquid phase.

It is within the scope of the invention to add water, glycol or similar material to the hydrocarbon and/or solvent in case the hydrocarbons are too soluble in the solvent. The addition of water in this case serves to decrease the solubility of the hydrocarbons and also to increase the selectivity of the solvent. Frequently it is necessary to add water especially to extract mixtures so rich in aromatics or olefins as to be mutually miscible with the solvent.

Usually more than one extraction is required in order to effect substantially complete separation of the unsaturated from the saturated hydrocarbons. In some cases, however, one extraction may be sufficient when it is required only to slightly lower the concentration of the unsaturated hydrocarbons in the mixture or in case the charging stock originally contains only a small percentage of unsaturated hydrocarbons.

After formation of the extract and raffinate phases, the solvent may be separated from the hydrocarbons by various means including: (1) distillation at increased temperature and/or reduced pressure; (2) adding water or the like in order to decrease the solubility of the hydrocarbons in the solvent and (3) counter-extracting the hydrocarbons from the solvent by contacting the extract phase with a secondary solvent which is immiscible with the first solvent and may comprise, for example, a paraffinic or naphthenic hydrocarbon of higher or lower boiling point than the solute. The second solvent is then separated from the solute by ordinary fractional distillation means.

The following examples are introduced for the purpose of further illustrating the novelty and utility of the present invention but not with the intention of unduly limiting the same.

Example I

A synthetic mixture of benzene and cyclohexane containing 17.5% by volume of benzene

70

75

was contacted with an equal amount by weight of succinonitrile ($CNCH_2CH_2CN$) at atmospheric temperature and atmospheric pressure. The extract and raffinate phases were separately withdrawn from the extraction zone and the dissolved hydrocarbons were separated from the solvent by distillation. It was found that the concentration of benzene in the hydrocarbons recovered from the extract phase was 82%, while the concentration of benzene in the raffinate phase hydrocarbons was only 13.7%. It is thus shown that the concentration of benzene in the charge was reduced from 17.5% to 13.7% in the raffinate by one extraction. By additional extractions, it is possible to reduce the benzene content of the raffinate to a very low figure.

Example II

A synthetic mixture of benzene and normal heptane containing 17.5% of benzene was prepared and extracted with β -hydroxypropionitrile ($HOCH_2CH_2CN$) at atmospheric temperature and atmospheric pressure. The extract phase and raffinate phase was separately withdrawn from the extraction zone and the hydrocarbons were separated from the solvent by water-washing. In this case, the volume of benzene in the extract hydrocarbons amounted to 67%, while the volume of benzene in the raffinate was 13%. Here, again, one extraction reduced the volume of benzene from 17.5% in the charge to 13% in the raffinate and continued extractions will reduce it to a still lower figure.

I claim as my invention:

1. A process for separating a mixture of organic compounds of different degrees of saturation which comprises treating said mixture with a solvent comprising a substituted aliphatic nitrile in which the nitrile and substituent groups are attached to different carbon atoms.

2. In a solvent extraction process for separating a mixture of hydrocarbons into fractions of differing degrees of saturation with respect to carbon-hydrogen ratio, the step of extracting said hydrocarbons with a substituted aliphatic nitrile in which the hydrocarbon content does not exceed about 64% by weight of the molecule and in which the nitrile and substituent groups are attached to different carbon atoms.

3. A process for separating a mixture of hydrocarbons of differing degrees of saturation which comprises treating said mixture with a selective solvent comprising a substituted aliphatic nitrile in which the nitrile and substituent groups are attached to different carbon atoms and in which the aliphatic portion of the solvent contains from 2 to 5 carbon atoms inclusive, the substituent group being strongly hydrophilic in nature.

4. A process for separating unsaturated hydrocarbons from saturated hydrocarbons which comprises treating a mixture of unsaturated and saturated hydrocarbons with a selective solvent comprising a substituted aliphatic nitrile in which the nitrile and substituent groups are attached to different carbon atoms and in which the aliphatic portion of the solvent contains from 2 to 5 carbon atoms inclusive, under conditions to form an extract phase and a raffinate phase.

5. The process of claim 4 further characterized in that said unsaturated hydrocarbons comprise olefins and aromatics.

6. The process of claim 4 further characterized in that said unsaturated hydrocarbons comprise olefins.

7. The process of claim 4 further characterized in that said unsaturated hydrocarbons comprise aromatics.

8. A process for separating an unsaturated hydrocarbon from a mixture thereof with a saturated hydrocarbon which comprises contacting the mixture with succinonitrile under conditions to form an extract phase and a raffinate phase.

9. A process for separating an unsaturated hydrocarbon from a mixture thereof with a saturated hydrocarbon which comprises contacting the mixture with β -hydroxypropionitrile under conditions to form an extract phase and a raffinate phase.

10. A process for separating a mixture of saturated and unsaturated hydrocarbons which comprises subjecting the mixture to solvent extraction with a substituted aliphatic nitrile containing a strongly hydrophilic substituent group and an aliphatic group having from 2 to 5 carbon atoms, said substituent group and the nitrile group being attached to different carbon atoms of the molecule.

11. A process for separating a mixture of saturated and unsaturated hydrocarbons which comprises subjecting the mixture to solvent extraction with a dinitrile containing an aliphatic group having from 2 to 5 carbon atoms, the nitrile groups of the compound being attached to different carbon atoms of said aliphatic group.

12. The process as defined in claim 10 further characterized in that said substituent group contains nitrogen.

13. The process as defined in claim 10 further characterized in that said substituent group comprises the hydroxyl radical.

14. A process for separating a mixture of sat-

urated and unsaturated hydrocarbons which comprises subjecting the mixture to solvent extraction with a nitro-nitrile containing an aliphatic group of from 2 to 5 carbon atoms, the nitro and nitrile groups of the compound being attached to different carbon atoms of said aliphatic group.

15. A process for separating a mixture of organic compounds of different degrees of saturation which comprises treating said mixture with a solvent comprising a substituted aliphatic compound containing as substituents at least two nitrile groups attached to different carbon atoms.

16. A process for separating a mixture of hydrocarbon compounds of different degrees of saturation which comprises treating said mixture with a solvent comprising a substituted aliphatic compound containing as substituents at least two nitrile groups attached to different carbon atoms.
